CARPET.

No. 17,773.

Patented Oct. 11, 1887.

UNITED STATES PATENT OFFICE.

ARTHUR L. HALLIDAY, OF NEW YORK, N. Y., ASSIGNOR TO THE BIGELOW CARPET COMPANY, OF CLINTON, MASSACHUSETTS.

DESIGN FOR A CARPET.

SPECIFICATION forming part of Design No. 17,773, dated October 11, 1887.

Application filed September 8, 1887. Serial No. 249,156. Term of patent 3½ years.

To all whom it may concern:

Be it known that I, ARTHUR L. HALLIDAY, of New York city, in the county and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

My design is made up of fan-shaped groups 20 of small conventionalized flower or leaf forms disposed at intervals over the face of the carpet. The intervening spaces are filled in and ornamented with circular flowers varying in

size, sometimes occurring alone, sometimes in clusters of three or four, and also in places with irregular forms partly scroll-like in character. The various groups and figures are connected by a continuous stem-work. Underneath the 25 groups and figures, and forming, as it were, a setting for the same, are leaves and flowers less prominently marked, but of larger size. These underlying leaves and flower forms resemble in shape the more prominent of the overlying 30 figures.

What I claim as new, and desire to secure by Letters Patent, is—

The design for carpets, consisting of the design substantially as shown.

ARTHUR L. HALLIDAY.
